UNITED STATES PATENT OFFICE

169,312

Therapeutic Lamp

Norris E. Goodrich, Battle Creek, Mich.

Application July 30, 1952, Serial No. 20,854

Term of patent 14 years

(Cl. D48—20)

To all whom it may concern:

Be it known that I, Norris E. Goodrich, a citizen of the United States of America, residing at Battle Creek, Michigan, have invented a new, original, and ornamental Design for a Therapeutic Lamp, of which the following is a specification, reference being had to the accompanying drawings, forming part hereof.

Figure 1 is a perspective front and side view of a therapeutic lamp, with the head of same in horizontal position, showing my new design.

Figure 2 is a perspective view similar to Figure 1 but with the head of the therapeutic lamp tilted downward.

Figure 3 is a perspective front view of the therapeutic lamp, shown in Figure 1, but with the head of same in vertical position.

Figure 4 is a perspective side view of the therapeutic lamp shown in Figure 3.

I claim:

The ornamental design for a therapeutic lamp, substantially as shown.

NORRIS E. GOODRICH.
